UNITED STATES PATENT OFFICE.

OLE J. ENGLUND, OF WORTHINGTON, MINNESOTA.

SOFA-BED.

1,225,942.

Specification of Letters Patent. Patented May 15, 1917.

Application filed November 26, 1915. Serial No. 63,648.

To all whom it may concern:

Be it known that I, OLE J. ENGLUND, a citizen of the United States, residing at Worthington, in the county of Nobles and State of Minnesota, have invented certain new and useful Improvements in Sofa-Beds, of which the following is a specification.

My present invention has special reference to the folding seat structure and spring mattress adapted to form a sofa bed, and consists primarily in the combination of the frame of a sofa provided with a compartment into which the seat structure of the davenport is adapted to fold, and from which the folding spring section of the bed is adapted to be drawn.

The special objects of my present invention are the provision of a structure which will be simple and economical to manufacture, which will be simple and positive in operation, and which will be firm and rigid in open position so as to be capable of giving satisfaction in any service to which it may be put.

I attain the above objects by means of the structure illustrated in the accompanying drawings, in which:—

Figure 1 is a front elevation of my davenport.

Fig. 2 is an end elevation of the davenport, one arm being broken away to show the end of the mattress or spring structure (lines 2—2 Fig. 1);

Fig. 3 is a view similar to Fig. 2, showing the spring portion extended and the seat portion of the davenport folded up within the compartment at the rear of the frame; and—

Fig. 4 is a top fragmental plan of the davenport as shown in Fig. 3.

Similar reference characters refer respectively to similar parts throughout the several views.

My davenport comprises the usual form of end pieces or arm 5, suitably secured to the wall 6 of the room within which my davenport is to be installed, the same forming the back of the davenport. A rectangular compartment extends rearwardly from the back of this wall comprising the top 7, rear wall 8, and end walls 9. Suitably spaced below the top of the wall 7, and rigidly secured to both ends 9, of the structure, are rails 10, upon which is adapted to slide the seat cushion 11 of the davenport, the

back cushion 12 thereof being connected to the rear of the same by means of a set of pivoted levers 13 and 14, the ends of the same being bolted respectively to the sections 11 and 12, their opposite ends being pivoted to one another at 15. Suitably secured to the walls 9—9 of the ends of the davenport, are a pair of rearwardly inclined angle irons, forming rails 16 and 17, upon which the rollers 18 which are journaled at the lower corners of a spring bed section 19 are adapted to travel. This spring bed section may be constructed in any of the well known forms, comprising primarily a rectangular frame, having a front wall 20, and over the frame is stretched a mesh 21.

The davenport being in the position as shown in Fig. 2, is converted into a bed, first by dropping the back section 12 upon the seat section 11 and sliding the same as a unit back into the rear compartment as shown in Fig. 3. The frame 20, containing the springs 21, of the bed, is then drawn forward from out of the rear compartment to the position as shown in Fig. 3, and as the rails 16 and 17 are inclined upwardly toward the forward edge, it is raised vertically until the rollers 18 drop into recesses in the rails at their respective upper and forward ends. To accommodate and take care of the weight at the outer end or front 20 of the spring structure when in this position, I provide a collapsible leg 22 pivoted at 23 to the under side of the forward end of the spring structure.

While I have illustrated and described herein certain specific means for carrying out my invention, it, of course, will be obvious to others skilled in the art to which it pertains, that numerous modifications or refinements thereof are possible without materially departing from the spirit of my invention. I therefore desire it understood, that such changes are contemplated within the scope of my invention as expressed in the appended claims.

What I claim is:—

1. A sofa bed comprising a back and ends, a compartment extending rearwardly from said back, a vertical back cushion, a horizontal seat cushion, said cushions being respectively hinged to one another at their adjacent ends and adapted to fold together and pass into said rear compartment, and a bed frame disposed below said cushions ex-

tending into said compartment and adapted to be withdrawn therefrom to form a bed.

2. A sofa bed comprising, in combination with back and end sections, a compartment 5 adjacent to and extending rearwardly from said back, seat and back cushions pivoted along their meeting edge, casters upon the bottom of said seat cushion, guideways upon the walls of said compartment and said end sections over which said cushions are adapted to travel, and a bed section mounted upon

inclined tracks substantially below said cushions.

In testimony that I claim the foregoing as my own I have hereto affixed my signature in the presence of two subscribing witnesses. 15

OLE J. ENGLUND.

Witnesses:

S. KIDLUND,
PETER THOMPSON.
